UNITED STATES PATENT OFFICE.

GEORGE W. MORRIS, OF PITTSBURG, PENNSYLVANIA.

CAR-AXLE-BOX LID.

SPECIFICATION forming part of Letters Patent No. 379,712, dated March 20, 1888.

Application filed November 23, 1887. Serial No. 255,984. (No model.)

To all whom it may concern:

Be it known that I, GEORGE W. MORRIS, a citizen of the United States, residing at Pittsburgh, in the county of Allegheny and State of 5 Pennsylvania, have invented new and useful Improvements in Car-Axle-Box Lids, of which the following is a specification.

My invention is directed to the improvement of the spring-lid for covering the opening in the face of the journal-box of car-axles, and for permitting access to the axle for oiling and for inspection.

The object of my improvement is to provide for holding the lid closed and permitting it to be opened by the simplest construction and application of the spring thereto, so that the lid may be fitted to its pintle-hinges and to the face of the journal-box before the function of the spring is rendered active, and by 15 which I obtain a lighter and more durable cover, in which the particular improvement resides in the simple and effective provision for applying the spring to the outer face of the lid, as illustrated in the accompanying drawings, in which—

Figure 1 is the blank for the lid. Fig. 2 is the lid formed complete for application to the face of the box and to receive and hold its spring. Fig. 3 shows the lid and its holding-spring in proper relation. Fig. 4 shows the spring. Fig. 5 shows a vertical section of so much of a journal-box as illustrates the use of my improved spring-lid when in closed position, and Fig. 6 is a similar view showing the spring-lid in open position for access to the journal-box.

A represents the shell of the journal-box, having the usual face-openings, *a b*, to receive the journal and for access to the box for oiling and inspection. As the lid is often open for the hasty inspection of the condition of the journal and its lubricant, it is important that it should be light and easily opened and closed. For this purpose I make the lid *B* of thin sheet-steel or other suitable metal stamped out in blank, as shown in Fig. 1, with corner edge projections, *c c*, to form pintle-hinge eyes or scrolls, a lower edge projection, *d*, to form a handle, a loop, *e*, punched out so as 40 to stand up from its outer face, and a punched-

out slot, *f*, the loop and the slot being in a middle line. The journal-box has a rounded projection, *g*, at its top, provided with a horizontal opening made to register with lid-eyes to receive the pintle *h*, which forms the 55 hinge for the lid. The spring *C* is a narrow plate of steel of suitable thickness, and has a right-angled lip, *i*, formed at one of its ends, adapted to fit into the slot in the lid. The spring is applied to the lid by slipping 60 its plain end up under the loop before the lid is hinged and fitted to the box; but the spring is only thus partially applied. After the lid is hinged and fitted to the box, then the spring is driven up from its lower angle-lip end 65 through the loop until the spring-lip reaches and is forced by the tension of the spring into the slot in the lid and holds it fast. In this position the upper end of the spring will pass over and bear upon a curved top part of the 70 box over the hinge between the pintle-hinge-forming eyes of the lid, so as to give a sufficient tension to the bearing end of the spring upon the top of the box to hold the spring firmly and closely down upon the open face of 75 the box. The spring is thus secured without rivets and permits the easy opening and closing of the lid. The lip of the spring and the loop of the lid secure the spring as permanently as if riveted together, greatly simplify the 80 construction, and reduce the labor and cost of applying both the lid and its spring.

An important advantage of my improvement is the provision by which the spring is driven to its locked position in the lid by simply driving the spring endwise in place, so as to render the locking action automatic by the force of the spring acting in a direction at right angles to that in which it is driven home. The spring is thus automatically locked endwise and secured from lateral displacement.

I prefer to form the spring-confining loop integral with the lid; but it may be a separate attachment thereto. When the lid is open, the spring acts to hold it in such position.

I claim—

1. An axle-box lid stamped out of sheet-steel, with a raised cross-loop and a cross-slot stamped therein, and a plate-spring having a right-angled end and fitted within said loop 90 100

and within said slot, combined with an axle-box having a top bearing for said spring, substantially as set forth.

2. In combination with an axle-box, a lid having the loop and the slot, and a spring having a right-angled end, whereby the spring may be locked to the lid by an endwise-driven movement, substantially as set forth.

3. The combination, with an axle-box, a lid having the pintle-hinge eyes, the loop and the

slot formed therein, as described, and a spring having a right-angled end adapted to be driven into the lid-slot, as and for the purpose stated.

In testimony whereof I have hereunto set my hand in the presence of two subscribing witnesses.

GEORGE W. MORRIS.
